(57) **CLAIM**

The ornamental design for a dual zone workstation, as shown and described.

DESCRIPTION

FIG. 1 is a perspective view of a dual zone workstation according to an embodiment of my design, wherein vertically adjustable zones of the dual zone workstation are shown in a first adjustment configuration thereof;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the dual zone workstation of FIG. 1, wherein the vertically adjustable zones of the dual zone workstation are shown in a second adjustment configuration thereof;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a perspective view of the dual zone workstation of FIG. 1, wherein the vertically adjustable zones of the dual zone workstation are shown in a third adjustment configuration thereof;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof; and,

FIG. 21 is a bottom plan view thereof.

The broken lines in the drawing illustrating display monitors supported by the dual zone workstation of the claimed design form no part thereof. A user of the dual zone workstation to provide environmental context for the claimed design forms no part thereof. All other broken lines illustrate portions of the dual zone workstation that form no part of the claimed design.
